PROCESS FOR MATRIX FORMING AND BEARER FOR THE SAME

Clarence E. Boutwell, Birmingham, Ala.

Application October 26, 1936, Serial No. 107,606

3 Claims. (Cl. 41—25)

My invention relates to bearers such as are employed around a type setup in making matrices for printing plates; also to a matrix made therefrom. As is well known, in the making of matrices, type or other design to be reproduced is placed in a chase. Around the type and inside the chase are placed metal bearers, which latter are locked in place in the chase and against the type by suitable locking devices. Heretofore, these bearers have consisted simply of flat surfaced metal bars having a height equal to the type face. Their purpose is to relieve the strain on the type and prevent displacement thereof when the matrix material is pressed into the printing setup. The matrix may consist of any suitable material which is deformable under pressure and capable of receiving and retaining an impression, such as soft metal, wax, resins, and other plastic materials.

Heretofore, in the making of matrices, employing bearers as above described, when pressure was applied to the matrix material, there was a natural lateral flow of the material toward the edges of the printing setup, caused by the displacement of the matrix material by the design to be produced, which flow was blocked by the pressure of the platen of the press bearing against the matrix material on the bearer. This blocked flow resulted in a concentration of pressure on the type adjacent the bearer, often causing the type adjacent the bearer to be broken off, and also causing faulty impressions to be made in the matrix material by the type adjacent the bearer. To relieve this difficulty in a measure, it has been the custom to interpose a border between the type and the bearer which served to minimize somewhat the concentration of pressure on the outer type faces. Another difficulty with bearers as heretofore employed has been that the outer edges of the matrix so formed has been of a height the same as the face of the type in the printing setup, so that after the matrix was formed, it has been necessary to machine down, or rout, the border around the printing setup, otherwise a plate formed from the matrix would receive ink from the inking rollers of the printing press, thus spoiling the reproduction from the plate.

I have discovered that the difficulties heretofore encountered may be entirely eliminated by affording a free lateral flow to the matrix material. In other words, I have found that the breaking of type around the bearer is not due so much to lateral flow of the matrix material, but to the concentration of pressure in the area

of the outer type members. By permitting a free lateral flow of the material under pressure, there is no greater concentration of pressure on the outer type members than the others, and as a result I obtain clear impressions without damage to the type.

It is accordingly a principal object of my invention to provide a bearer for matrix making which shall afford a free flow of the matrix material around the outer edges of the type setup; a further object is to provide a bearer of such configuration that a matrix is formed having sides sloping away from the type face, whereby a plate made from such a matrix shall have its sides around the printing setup sloping downwardly from the type faces when viewed with the type faces uppermost and thus require no machining or routing to finish them.

A preferred embodiment of my invention is illustrated in the accompanying drawing forming a part of this specification, in which

Fig. 1 is a fragmentary plan view of a printing setup surrounded by my improved bearers;

Fig. 2 is a sectional view taken along the line II—II of Fig. 1, and showing a matrix pressed into the type setup; and

Fig. 3 is a sectional view showing the matrix and a plate formed therein, the latter removed from the matrix.

Referring to the drawing, my improved bearer is made up of a number of corner pieces 10 and side pieces 11 which may be fitted together as shown, and as is well understood, to conform to the shape and size of the type setup 12. The bearer pieces are all of equal height so as to adapt them to be placed end to end around a printing setup and form a continuous bearer therefor. Each bearer piece has a flat upper surface 13 the same height as the type faces 14, but spaced therefrom a distance of about a half an inch. 40 Adjacent the type, the inner wall 15 of the bearer piece is of a height equal to the shoulder 16 of the type or printing setup. A groove 17 is formed in each bearer piece, which is preferably made by sloping the upper surface 18 downwardly 45 away from the top of the wall 14 for substantially the full width of the groove and forming a vertical wall 19 from the bottom of the groove to join the upper flat surface 13. The area described by the groove 17 thus accommodates the matrix 50 material displaced by the type or reproductions on the printing setup, when forming a matrix.

When a matrix 21 of any suitable matrix forming material is pressed downwardly on to the printing setup, as shown in Fig. 2, the platen of 55

the press (not shown) bearing downwardly on the matrix material, the vertical wall 19 impedes its flow past the groove 17, while the displaced matrix material flows freely into the groove 17.

5 As before pointed out, I have found that by thus providing for the free flow of the matrix material with means to stop an excess flow, the strain on the outer type members is greatly reduced and the matrix is formed with perfect reproduction

10 without breaking off the outer type faces. It will also be noted from Fig. 2 that the sides 22 of the matrix 21 slope downwardly from the type faces, as viewed in Fig. 2.

In Fig. 3 the matrix 21 is shown in inverted position with a plate 23 withdrawn therefrom. The plate 23 has sloping sides 24 conforming to the surfaces 22 of the matrix, which are of a height lower than the printing surfaces 26 formed on the plate. It will be obvious from a consideration of Fig. 3 that such a plate requires no machining or routing before mounting in a printing setup. The only preparation required for the plate 23 is a trimming of the edges, as shown at

27.

25 The downwardly and inwardly sloping surfaces 22 of the finished matrix have another important function, in that, in making a plate from such a matrix, and employing plastic material, the sloping sides cause the plastic material to flow toward and into the depressions 30, made by the printing setup. The form of the matrix 21 thus lends itself to the easier production of plastic plates therefrom, as well as having the other advantages heretofore mentioned.

35 From the foregoing it will be apparent that I have devised an improved bearer for making matrices which is simple of construction and which cooperates in forming a matrix having particular advantages in forming printing plates

40 from plastic materials.

While I have shown my invention in but one form, it will be obvious to those skilled in the art that it is not so limited, but is susceptible of various changes and modifications, without de-

parting from the spirit thereof, and I desire, therefore, that only such limitations shall be placed thereupon as are imposed by the prior art or as are specifically set forth in the appended claims.

5

What I claim is:

1. A bearer for printing setups in making matrices from metals, resins and the like involving pressures endangering the type characters comprising a plurality of similar side pieces and 10 similar corner pieces adapted to be placed end to end around a printing setup and form a continuous bearer therefor, each of said bearer pieces having a vertical inner wall adapted to bear against the side of the printing setup and being 15 shoulder high to the printing surface thereof, an upper surface sloping downwardly from the vertical inner wall and intersected by a vertical side wall to form a groove having a capacity sufficient to accommodate laterally displaced matrix material, and a flat outer, upper surface equal in height to the printing surface to impede further flow of matrix material.

2. A bearer for printing setups in making matrices in a press from plastic material and involving the use of pressures sufficient to break off type faces, comprising a bearer member shoulder high with respect to the setup and sloping downwardly therefrom to form a groove to accommodate the lateral flow of matrix material, 30 and an outer portion type high with respect to the set up to form a stop for the platen of the press and to impede excess flow of material.

3. The method of making matrices for printing plates from soft metals, resins and the like involving pressures such as to endanger type characters, which comprises providing for free lateral flow of matrix material around the setup sufficient to accommodate the laterally displaced matrix material when pressed into the setup, and impeding the lateral flow beyond said point to provide for accurate reproduction of the type characters in the setup, especially around the edges thereof.
